UNITED STATES PATENT OFFICE.

SAMUEL P. JOHNSTON, OF SAN MATEO, CALIFORNIA, ASSIGNOR TO CALIFORNIA COTTON MILLS COMPANY, OF SAN FRANCISCO, CALIFORNIA, A CORPORATION OF CALIFORNIA.

CONTAINER.

1,210,075.

Specification of Letters Patent. Patented Dec. 26, 1916.

Application filed February 23, 1915. Serial No. 10,128.

To all whom it may concern:

Be it known that I, SAMUEL P. JOHNSTON, a citizen of the United States, residing in the city of San Mateo, county of San Mateo, State of California, (whose post-office address is San Mateo,) have invented new and useful Improvements in Containers, of which the following is a specification.

This invention relates more particularly to telescoping boxes adapted to contain bed clothing and the like.

Among the objects sought to be accomplished are, to provide a sanitary container for bed quilts and other like articles, liable to contamination by handling or exposure; that provides for the visual examination of the article contained within the box without removal therefrom; that provides means for sealing the box to prevent the removal of the contents without mutilating the seal; that provides a supplemental cover to protect the visible portion of the contents from exposure to the light.

Other objects and advantages will appear as the description progresses.

In the drawing accompanying and forming part of the present specification, to which like reference characters have been applied, a simple form of putting this invention into practice is shown.

I do not wish to be understood as confining this invention to the disclosures made in said drawing and description as many variations may be introduced, within the spirit of this invention, as defined in the claims succeeding the said description.

It is common practice in selling and exposing for sale bed clothing, toweling and like articles, to pile them on counters, or place them within reach of the hands of possible buyers. This practice has proved very undesirable. It is a human failing to handle attractive articles within reach, whether contemplating purchase or not; inasmuch as the hands of the public are not always in a sanitary condition such merchandise is liable to contamination and the accumulation of diseases, liable to be communicated to an innocent purchaser; and this exposure and handling subjects the goods to unnecessary soiling, fading and the danger of mutilation, placing an unnecessary burden on the merchant who is compelled to sell such pieces at an unprofitable figure in order to dispose of them.

The use of a container such as herein illustrated and described, exposes the merchandise sufficiently to enable the customer to choose the color scheme, and note the visible quality of the finish, while the article is retained within a sanitary package, safe from the dangers above set forth. This method enables the salesmen to protect the goods until a *bona fide* purchaser desires a closer examination, and protects the ultimate consumer from the dangers of contagion so often communicated through such sources.

In the drawings: Figure 1 is a perspective looking at the front of the container, with the supplemental cover partially removed. Fig. 2 is a fragmentary detail in cross section showing the interrelation of the various parts. Fig. 3 is a diagrammatic front elevation of a modified form of cover for the transparent opening.

In detail the construction illustrated in the drawing includes a telescoping box comprising the outer casing 1 and the inner casing 2, placed one within the other in the usual manner, to form an inclosing box having the bottom 3, top 4 and the side walls 5 and 6, completely inclosing the articles contained therein. The top 4 is provided with a center opening 7 covered by a sheet of isinglass 8 pasted around the margin of the opening 7. The object of the isinglass or any other suitable transparent material that may be used, is to expose the contents of the box to view while protecting them against handling.

To prevent the separation of the outer and inner casings 1 and 2, the tape or ribbon 9 passes entirely around the box and is tied with an ornamental knot as at 10. This knot can be sealed with wax or by a paster confining its ends, to prevent the removal of the tape without mutilating the seal. It is often quite proper in the course of making a sale to open the box and permit the purchaser to handle the contents. To permit this the paster or seal 11 is pasted over the tape confining it to the top 4. See Fig. 1. This permits the knot 10 to be untied and the contents removed; at the same time creating the impression that the box is sealed, conveying to the "shopper" the impression that the box cannot be opened, leaving such action to the discretion of the salesmen.

To protect the contents of the box from the fading action of light, and to protect the top 4 from soilure while in stock, the supplemental cover 12 having the flanges 13 extending down over the edges of the outer casing 1 is provided. When the article is exposed for sale or used in window display this cover can be laid aside or placed over the bottom 3 of the box.

Having thus described this invention, what I claim and desire to secure by Letters Patent is:

A container including an outer and inner casing telescoping together, an opening in one of said casings, a sheet of transparent material sealing said opening, a tape surrounding said casing, a seal secured to said tape and said casing, said container being openable without breaking the seal, and a detachable supplementary covering engaging and covering said outer casing.

In testimony whereof, I have hereunto set my hand this 10th day of January, 1915.

SAMUEL P. JOHNSTON.
